ALFRED GRIEB, OF ELIZABETH, NEW JERSEY, ASSIGNOR TO THE SINGER MANUFACTURING COMPANY, A CORPORATION OF NEW JERSEY.

OVERSEAMING SEWING-MACHINE.

932,272.

Specification of Letters Patent. Patented Aug. 24, 1909.

Application filed April 13, 1907. Serial No. 368,035.

To all whom it may concern:

Be it known that I, ALFRED GRIEB, a citizen of the United States, residing at Elizabeth, in the county of Union and State of New Jersey, have invented certain new and useful Improvements in Overseaming Sewing-Machines, of which the following is a specification, reference being had therein to the accompanying drawings.

10 This invention relates to certain improvements in the overseaming sewing machine forming the subject of my application Serial No. 321,952, filed June 16, 1906, and has for its objects, among others, to improve the 15 constructive features of the frame so as to permit of a more effective arrangement of the operative parts, to insure convenience in assemblage of the latter and removal for repair or replacement, to improve the effectiveness of operation and durability of the parts subjected to the greatest wear in operation, and to improve the general appearance and convenience of manipulation of the machine.

5 In its preferred form, the machine is provided with a rectilinearly reciprocating needle and two coöperating thread-carrying loopers or thread-carriers by which a three-thread overseam is produced.

0 As regards certain of its characteristic features, the present improvement is not limited to any particular type of loopers, as this will depend largely upon the kind of overseam desired, and the term "thread-carriers" as used herein is employed in its broader sense to include thread-loop handling implements of any suitable form coöperating with the needle in the production of stitches.

While the character of the tension and stitch-setting devices determines the position of interlock of the threads, such members are preferably designed to locate such interlock along the edge of the material enclosed by the overseam so as to provide a species of braid to cover such extreme edge.

In the machine disclosed in my prior application, a bracket in the form of a flat plate affording the bearings for the inclined needle-bar extended forwardly from the back of the machine and carried the fulcrum-pin for the needle-actuating rock-lever, the rearward end of which was connected with the eccentric-rod embracing an eccentric upon the main-shaft. The parallel relation of the needle-actuating lever with the knife-

lever and other operative parts thus made it necessary to employ a series of closely adjacent actuating eccentrics upon the main-shaft for imparting the requisite motion to such parts, and the necessary use of an eccentric for imparting the requisite long throw to the needle-bar involved the employment of an eccentric of large diameter in conjunction with a needle-actuating lever having a relatively short arm connected with the eccentric-rod for production of such motion. This was found in practice to produce an excess of friction between the eccentric and its strap and to involve a somewhat harsh driving relation between the eccentric-rod and the needle-actuating lever which produced excessive wear of such parts and noise in the operation of the machine at high speeds consequent upon such wear.

By the present improvement I have replaced the needle-bar-supporting bracket, disposed parallel with the line of feed, by an overhanging bracket-arm arranged longitudinally of the main-shaft and providing an inclined transverse fulcrum for a longitudinally disposed needle-bar-actuating lever, thus affording an arrangement involving a longer lever fulcrumed substantially at the center of its length for actuation from a point in the main-shaft distant from the work-engaging members of the stitch-forming, feeding and trimming devices. By this means I am enabled to provide a crank of small diameter upon the main-shaft having the requisite throw for imparting the required reciprocating movements to the needle-bar so as to reduce to a minimum the friction of the mechanism, to provide easier and quieter movements of the mechanism and to materially increase the durability of the latter. By the new location of the needle-bar-actuating lever the latter is so arranged as to permit the easy removal of the cutter and presser-foot levers, and the latter may be assembled and removed independently and without disturbing or affecting the other operative parts of the machine.

The upright portion of the bracket-arm is detachably secured upon the bed of the machine by screws in a well-known manner, and its lateral portion affords a suitable support for the inclined needle-bar lever fulcrum-pin. The laterally extending portion of the bracket-arm is twisted and provided with an inclined head sustaining the similarly inclined needle-bar, between which and one of

the bearing bosses for the fulcrum-pin of the needle-bar-actuating lever is interposed the forward arm of the latter having the usual link connections with a collar upon the needle-bar, while a rearwardly extending arm of said lever is disposed upon the opposite side of the bracket-arm and is connected to the upper end of the pitman whose opposite end embraces the actuating crank upon the main-shaft. This peculiar form of bracket-arm not only affords a rigid support for the operative members of the needle-actuating mechanism, but provides a recess for the operative end portion of the needle-bar-actuating lever and the take-up device of which the same constitutes an operative member, as also its connections with the needle-bar, and materially improves the appearance of the machine.

In the accompanying drawings, Figure 1 is a front side elevation of the machine with the balance-wheel and the greater portion of the work-plate omitted and a part of the front of the casing broken away to expose the operative parts behind the same. Fig. 2 is a front end elevation and Fig. 3 a plan of the machine. Fig. 4 is a transverse sectional elevation through the right-hand end of the needle-bar-actuating crank. Fig. 5 is a detached sectional elevation representing a portion of the feed-bar, the feed lifting eccentric and intermediate connections. Figs. 6, 7 and 8 are detached views representing in side elevation the needle and looper mechanism at different stages of the stitch-forming cycle. Fig. 9 is a detached sectional elevation of one of the feed-rocker supports. Fig. 10 is a perspective view of the trimmer-guard, cord-guide and adjustable carrier-bar therefor with depending oil-guard plate, and Fig. 11 an end elevation of the same. Fig. 12 is a sectional elevation of the head of the trimmer-bar, with the upper trimmer-blade, and Figs. 13 and 14 are perspective views, respectively, of the upper knife-carrying block and its removable gib provided with the knife-channel. Fig. 15 is a detached view, partially in section, of the lower knife-clamping member.

The machine is constructed with the base 1, having journaled in suitable standards the longitudinally extending main-shaft 2 shown supported at its rearward end by a bushing 3 and provided adjacent thereto with a needle-actuating ball-crank 4. The top of the base 1 is provided with a seat to which is fitted and secured by means of screws 5 the foot 6 of a bracket-arm formed with an upright portion 7 joining the overhanging member 8 comprising a straight lateral portion 8 merging into an inclined portion 9 carrying at its forward end the inclined head 10 which is provided with bearings 11 for the similarly inclined needle-bar 12 carrying the eye-pointed needle 13.

The needle-bar is provided with the usual collar 14 fixed thereon and having a lateral lug to which is connected by a pivotal pin 15 a link 16 connected at the opposite end by means of a pin 17 with the forward end of a rock-lever 18 mounted upon an inclined fulcrum-pin 20 journaled in the inclined transverse bearing bosses 21 of the bracket-arm and having a rearwardly extending crank-arm 22 provided with a ball 23 embraced by the upper end of a pitman 24 embracing at its lower end the actuating crank 4 of the main-shaft. The ball 23 carries an axial stud-pin 25 embraced by a forked lug 26 secured to the adjacent end of the pitman 24 by means of a screw 27. The two arms 18 and 22 of the needle-bar actuating rock-lever and their connections with the needle-bar lie in inclined planes parallel with the latter, and are preferably constructed of substantially equal length, and the actuating crank 4 is given such a throw as to communicate by easy movements the requisite length of stroke of the needle-bar.

The needle-thread-engaging or primary looper 28 is represented herein of well-known U-form with its blade provided with thread-eyes for carrying a lower thread and having its shank secured by means of a set-screw 29 within a transverse socket of the vibrating carrier 30 having a hub journaled upon a stud 31 fixed in a boss 32 upon the base 1.

The primary-looper-thread-engaging or secondary looper 33 has its blade similarly provided with means for carrying a second lower thread and has a flange 34 at the base of its shank fitted to and secured by means of a screw 35 upon a suitable seat at the upper end of a vibrating carrier 36 having a hub in the form of a long sleeve 37 fitted upon a transverse shaft 38 and maintained from endwise movement thereon by the abutting adjacent ends of the split bushings 39 fitted within the bosses 40 of the base 1 and adjustably clamped upon said shaft by means of the set-screws 41 entering said bosses. The looper-carrier hub 37 is provided with a lateral crank-arm 42 having a ball 43 embraced by the lower end of a pitman 44 whose opposite end embraces the ball-crank 45 carried by a collar 46 mounted upon the forward end of the main-shaft 2. The ball 43 is provided with an axial stud-pin 47 embraced by a forked lug 48 secured to the pitman 44 by means of the screw 49. The carrier 36 has a lateral arm 50 connected by means of a pivotal screw-pin 51 with one end of a link 52 whose other end is connected by means of a pivotal screw-pin 53 with the shank of the primary looper-carrier 30, the members 36, 50, 51 and 52 forming a toggle connection between the rocking hub 37 and the primary looper-carrier for giving the looper 28 its desired operative movements, while the secondary looper 33 derives its vi-

ibrating operative movements from the rocking hub 37 through the latter's connection with the ball-crank 45 carried by the main-shaft.

5 The lateral arm 50 of the secondary looper-carrier is provided with a thread-eye 54 having a foot secured in position by means of a fastening-screw 55, and the primary looper-carrier also has an open thread-hook 56 projecting laterally therefrom and secured in position by means of a fastening-screw 57. The primary looper-thread *a* is led from the thread-supply from the rear of the base 1 upwardly to the tension device 58, through 10 the guide-tube 59 in the forward main-shaft bearing to the thread-eye 54, and thence through the eyes and connecting groove in the blade of the looper 28 to the work. The secondary looper-thread *b* is led from the 15 thread supply through a guide-eye in the plate 60 upon the top of the bracket-arm to the tension 61 and thence to the thread-hook 56 from which it is led downwardly under the stationary thread-guide 62 and upwardly through the eyes and intermediate groove in the blade of the secondary looper 25 33 to the work.

An upper-thread take-up arm 63 provided with open guide-eyes 64 and 65 is secured by 30 means of screws 66 upon the needle-bar-actuating lever arm 18 in such position that its guide-eye 64 is adapted to move into and out of alinement with a thread-hole 67 in the projecting lug of the collar 14. The needle-thread *c* is led from the thread supply through the tension device 68 and the stationary guide-eye 69 to the thread-hole 67, and thence to the thread-eye 64 and through a guide-eye 70 in a plate 71 adjustably secured by means of a screw 72 to the upper bearing 11 of the bracket-arm, from which guide-eye 70 the needle-thread leads downwardly along the needle-bar and needle to the needle-eye and thence to the work.

45 In the operation of the thread-handling devices, the needle descends to its lowest position, as represented in Figs. 1 and 6, and at the beginning of its return movement throws out the usual loop which is entered by the primary looper 28 which rises to the position represented in Fig. 7, being met at substantially the level of the throat-plate 73 by the secondary looper, whose continued advance movement causes it to pass through the primary looper-loop, engaging and deflecting the same by its lateral shoulder 33^X and to present its own loop for passage of the needle in the latter's succeeding descent as represented in Fig. 8. As the three thread-carrying members return to their initial positions preparatory to repeating the described operations, as represented in Figs. 1 and 6, each of the loopers backs out of the respective thread-loop which it has previously taken and the threads are drawn up to complete the stitch by the action of the several thread-controlling members.

As indicated in dotted lines in Fig. 1, when the needle is in its highest position, the take-up member 63 is at the end of its stitch-setting and thread-drawing operation upon the needle-thread, the thread-eyes 64 and 67 being at their greatest distance apart. As the needle commences to descend for the production of a new stitch, the thread-eye 64 approaches the needle-bar and the thread-hole 67 descends for producing a differential thread-slackening action, which continues practically until the thread-eyes 64 and 67 are in substantial alinement in the direction of reciprocation of the needle, at which point their further descent in respect of the stationary thread-eye 70 produces a further pull upon the needle-thread acting in conjunction with the simultaneous pulls upon the looper-threads to draw up the previous stitch and properly locate the interlock of the threads preparatory to the final setting operation which is performed as the needle again rises to its highest position and while its loop last formed is still around the primary looper, as represented in Fig. 8.

As shown in Figs. 1 and 6, the loopers are in their retracted positions, and their thread-controlling members 54 and 56 are in their extreme operative positions for drawing up their respective threads. As the loopers approach one another to the positions represented in Fig. 7 their respective thread-controlling members, each mounted upon the carrier of the other, approach the thread-guiding eyes afforded by the members 28 and 62, respectively, so as to give up the necessary slack to prevent disarrangement of the seam while maintaining their threads under substantial control. The further movement of the loopers to the other extreme position represented in Fig. 8 causes the straightening of the toggles 50, 51, 52, and consequent dwell of the primary looper 28 while the secondary looper continues its advance for presentation of its thread to the needle, its thread-engaging shoulder 33^X in such movement catching the looper-thread *a* and deflecting it so as to take up the slack which would otherwise be produced by the continued movement of the controlling member 54 with the carrier 36 during the dwell of the looper 28. As the secondary looper reaches this extreme position its more rapid movement than that of the controlling member 56 produces the tightening of the secondary looper-thread *b* which acts, in conjunction with the simultaneously tightened needle-thread and primary looper-thread to complete the positioning of the component members of the stitch in process of formation simultaneously with the setting of the stitch previously formed as before described. It has been found in practice that when

the machine is provided with two needle-threads carried by a single needle, less take-up action is required in the production of the stitches, and for this reason the second 5 thread-eye 65 in the take-up arm 63 is provided, both needle-threads being introduced into the eye 65 and the eye 64 being left unthreaded under such condition.

As herein represented, the feeding mechanism comprises a feed-dog 74 upon the feed-bar 75 provided with the usual link 76 embracing the feed-eccentric 77 upon the main-shaft 2 and having its rear end pivotally connected with upright arms 78 carried by 10 the feed-actuating rocking sleeve 79 fitted upon the stationary longitudinal shaft 80 and maintained from endwise movement thereon by the abutting adjacent ends of the split bushings 81 fitted within the bearing 15 bosses 82 of the base 1 and adjustably clamped upon said shaft by means of the set-screws 83 entering said bearing bosses, as shown specifically in Fig. 9.

The rocking sleeve 79 is provided with a 20 lateral arm 84 connected with the upper end of a link 85 whose lower end is adjustably secured by means of a bolt 86 with the slotted segmental-arm 87 of a rocker pivotally mounted upon a fixed fulcrum-pin 88 and 25 having a second arm 89 whose extremity is pivotally connected by means of a pin 90 with one end of an eccentric-rod 91 having at its opposite end a strap embracing the feed-actuating eccentric 92 upon the main-shaft 2 adjacent the needle-actuating crank. 30 The link 85 carries an upwardly projecting pointer-arm 93 extending into proximity and co-operating with the graduated segment-bar 94 which is secured upon the work-plate of 35 the machine.

The length of the feeding movement is obviously determined by the adjustment of the lower end of the link 85 in the slotted segmental-arm 87, and such link may be set to 40 produce the desired length of stitch by bringing the pointer 93 to the proper graduation upon the segment-bar 94 when the link 85 is in radial relation with the segmental arm 87.

50 The frame of the machine is provided with an upright bearing plate 95 carrying the lateral fulcrum-stud 96 embraced by the boss 97 of the presser-bar 98 having secured to a suitable transverse seat at its forward 55 end by means of a fastening-screw 99 the shank of the presser-foot 100 having the upturned forward portion 101, and having a sole portion normally pressed upon the throat-plate by means of the pressure-spring 60 102 interposed between a shoulder of the presser-bar and the end of an adjusting screw 103 entering a socket in the head of the bracket-arm, in a well-known manner. The usual lifting cam-lever 104 is mounted upon 65 the bearing-plate 95 by means of the pivotal

pin 105 and is adapted to engage the eccentric head of a screw-stud 106 carried by the presser-bar 98 and provided with the lock-nut 107.

The trimming mechanism comprises an upper reciprocating knife 108 and a lower stationary-knife 109. The knife 108 is carried at the forward end of a vibrating bar 110 which is pivoted at the opposite end upon a fixed fulcrum-pin 111 carried by the bearing-plate 95 and is pivotally connected intermediate its ends by a bolt 112 with the upper end of an eccentric-rod 113 whose lower end is provided with a strap 114 embracing the trimmer-actuating eccentric upon the main-shaft. The forward end of the trimmer-bar 110 is forked to form a pair of spaced bearing members 115 to which is fitted a tubular knife-carrying shaft 116 having at one end a head 117 provided with a diametrical channel in which is removably fitted a gib 118 having a longitudinal groove or channel 119 to which the knife-blade 108 is fitted. The channel in the head 117 is closed by means of a cap-piece 120 secured thereto by screws 120^x and the point of a long clamping screw 121 entering the tubular shaft 116, by engaging the back of the gib 118, serves to clamp the same with the blade 108 in position within the head 117.

95 The knife-shaft 116 is provided intermediate its bearings with a collar 122 having a bifurcated lateral lug 123 embracing a guide-bar 124 secured to and extending between the bearing members 115, such collar being 100 adjustably secured upon the knife-shaft by means of a set-screw 125, and a spring 126 is interposed between the collar 122 and one of the bearing members 115 whereby the upper knife 108 is pressed normally in contact with 105 the lower knife 109.

The lower knife-blade 109 is shown fitted to an inclined channel in a carrier-block 127 and clamped thereon by engagement thereof with the laterally notched head 128 of the 110 pin or plug 129 passing through such block and having upon its threaded opposite end portion a milled clamping nut 130 by which the head 128 is drawn into operative engagement with the blade 109 entering its notch. 115 The carrier-block 127 is mounted in suitable guide-ways of the frame, and is provided with lugs 131 having adjustable stop-screws 132 whose points are adapted to bear alternately upon a laterally projecting portion 120 133 of the main frame to limit the movement of such block and knife carried thereby transversely of the direction of feed. The adjustment of this knife-carrying block is effected by means of a screw 134 tapped into 125 the member 133 of the machine frame and having a swivel connection with a slotted lug 135 of the block 127, and it may be securely clamped in any position of adjustment by means of the fastening screw 127^x passing 130

through a slot 133^x in the member 133 of the machine frame and entering the block 127.

As will be readily understood, the shifting of the working position of the stationary 5 knife 109 produces a corresponding lateral movement of the reciprocating knife 108 which follows the same under the yielding action of the spring 126.

The carrier-block is provided with a needle-guiding plate 136 having an upper edge 10 slightly inclined to the needle-path to insure against the deflection of the needle into the looper-path and the consequent breaking of the needle.

15 The side of the base 1 adjacent the foot 6 of the bracket-arm is provided with a longitudinal seat to which is fitted the shank 137 of a bracket member provided with a longitudinal slot 138 entered by the shank of a 20 fastening-screw 139 tapped into the base and adapted to secure such bracket-piece adjustably thereon. To the forward end of said bracket-piece is attached by means of screws 140 the foot 141 of an angular shield- 25 plate having an upturned flange 142 inclined at an angle similar to that of the forward portion 101 of the presser-foot, and having its end disposed close to the upper trimmer-knife 108 whereby it is adapted to 30 strip the trimmings from the body of the fabric whose edge is to be provided with the overseam. By loosening the fastening-screw 139, the shield-plate with the supporting bracket-piece 137 may be properly 35 adjusted when the trimming knives are reset for different widths of overseam.

As disclosed in my pending application before referred to, to the forward end portion of the flange 142 of the shield-plate is 40 fastened by means of screws 143 the shank 144 of a cord-guiding member 145 which is provided upon its inner side with a longitudinal cord-receiving groove 146, the edge of the member 145 being spaced slightly from 45 the depending lip 142^x to afford a longitudinal threading slit for the cord-guiding channel afforded by the grooved member 145 and the opposed lip 142^x, as indicated in Fig. 11. The delivery end of the cord-guide has a transverse notch 147 so disposed as to deliver the cord adjacent to and slightly below the top of the throat-plate, and the member 145 is formed with a notch 50 148 through which the cord *d* is adapted to be led from the eye 149 of the thread-guiding plate beneath the tension device 68, the cord being threaded through the longitudinal slit in the guiding channel 146 and directed by the latter to the lower edge of the material 55 to which it is secured by the overseam.

The bracket-piece 137 carries a depending shield-plate 150 serving to shield the looper-threads from the rotating parts beneath the work-plate, and the side of the base nearest the operator is inclosed by means of a re-

movable plate 151 having key-hole slots 152 (Fig. 1) receiving the fastening-screws 153 and 154, and a thin sheet-metal door 155 forming a continuation thereof and hinged along its lower edge to a plate 156 secured 70 by screws 157 to the base-plate. The upper edge of the sheet-metal door is adapted to latch itself upon the wire fastening-pin 158 secured to the bracket-piece 137 by means of one of the screws 140, as represented in 75 Figs. 1 and 10. A finger-piece 159 is shown applied to the cover-plate 151 for use in the removal of the latter for inspection of the looper mechanism; but it will be observed that in the threading of the loopers, it is 80 necessary only to open the door 155 for access to the secondary looper, the primary looper being accessible, by bringing the same into its advance position above the throat-plate, as indicated in Fig. 8. 85

The looper-actuating mechanism is housed by means of a swinging work-plate section 160 pivoted to the machine-base by a fulcrum-screw 161 and having a depending apron 162 inclosing the looper-actuating 90 mechanism upon three sides and provided along its lower edge with an oil-receiving flange 163 having an upturned lip 164, this flange having a slight downward inclination from front to rear, so that any oil thrown 95 from the looper-actuating mechanism will be caught in the same and carried backwardly to be discharged into the channeled bed or drip-pan with which the machine is customarily provided when in operation. 100

By the foregoing description, I have indicated the preferred construction and arrangement of the various parts of the machine, but it is to be understood that the same may be varied to a considerable degree without departure from the scope of the present invention. 105

What I claim herein is:—

1. In an overseaming sewing machine, the combination with the frame, a throat-plate 110 thereon, a shaft mounted in and arranged longitudinally of said frame, a needle reciprocating in a path inclined in respect to said throat-plate and in a plane transverse to said shaft, operating mechanism for said needle 115 comprising an actuating rock-lever extending longitudinally in relation to said shaft and movable upon a fulcrum disposed in substantially perpendicular relation both to said shaft and to the path of movement of the 120 needle, a connection between said lever and said needle, actuating means for said lever, and overseaming looper mechanism arranged below said throat-plate and comprising two thread-carriers relatively movable in 125 parallel planes perpendicular to said throat-plate and inclined relatively to said needle-path, and means for actuating said thread-carriers whereby thread-loops are passed through loops of needle-thread below the 130

- throat-plate and thread-loops are presented for passage of the needle above the throat-plate.
2. In an overseaming sewing machine, the combination with the frame, a throat-plate thereon, a crank-shaft mounted in and arranged longitudinally of said frame, a needle reciprocating in a path inclined in respect to said throat-plate and in a plane transverse to said shaft, operating mechanism for said needle comprising an actuating rock-lever extending longitudinally in relation to said shaft and movable upon a fulcrum disposed in substantial perpendicular relation both to said shaft and to the path of movement of the needle, a connection between said lever and said needle, a crank-rod with one end embracing the crank of said crank-shaft and the other end connected with said lever, and an overseaming looper mechanism arranged below said throat-plate and comprising two thread-carriers relatively movable in parallel planes perpendicular to said throat-plate and inclined relatively to said needle-path, and means for actuating said thread-carriers whereby thread-loops are passed through loops of needle-thread below the throat-plate and thread-loops are presented for passage of the needle above the throat-plate.
3. In an overseaming sewing machine, the combination with the frame comprising a base portion and an overhanging bracket-arm, a throat-plate mounted upon said base-portion, a crank-shaft mounted in bearings in and longitudinally of said base-portion, a reciprocating needle-bar carrying an eye-pointed needle and mounted in bearings in said bracket-arm inclined in respect to said throat-plate and in a plane transverse to said shaft, needle-bar operating mechanism comprising an actuating rock-lever extending longitudinally in relation to said shaft and having offset forwardly and rearwardly extending arms, the former disposed in front of and the latter at the rear of the bracket-arm, said lever having a fulcrum intermediate its ends disposed in substantially perpendicular relation both to said shaft and to the path of movement of the needle, a collar fixed to said needle-bar, a link connection intermediate said collar and the forwardly projecting arm of said rock-lever, a crank-rod with one end embracing the crank of said crank-shaft and the other end connected with the rearwardly extending arm of said rock-lever, and overseaming looper mechanism arranged below said throat-plate and comprising two thread-carriers relatively movable in parallel planes perpendicular to said throat-plate and inclined relatively to said needle-path, and means for actuating said loopers whereby thread-loops are passed through loops of needle-thread below the throat-plate and thread-loops are presented for passage of the needle-loops above the throat-plate.
4. In an overseaming sewing machine, the combination with the frame comprising a base portion and an overhanging bracket-arm, a throat-plate upon said base portion, a longitudinal crank-shaft mounted in bearings in said base portion, a reciprocating needle-bar carrying an eye-pointed needle and mounted in bearings in said bracket-arm inclined in respect of said throat-plate and lying in a plane transversely of said shaft, needle-bar operating mechanism comprising a longitudinally extending actuating rock-lever movable upon a fulcrum intermediate its ends substantially perpendicular to the needle-path, a collar fixed to said needle-bar and provided with a thread-eye, a link connection intermediate said collar and a forwardly projecting arm of said rock-lever, a crank-rod with one end embracing the crank of said crank-shaft and the other end connected with a rearwardly extending arm of said rock-lever, a thread-guiding member fixed upon the bracket-arm and having a thread-eye adjacent said needle-bar, a thread-controlling member carried by and movable with said rock-lever and provided with a thread-eye adapted to engage the needle-thread intermediate the thread-eyes of said collar and fixed thread-guide, and overseaming looper-mechanism arranged beneath said throat-plate and comprising means whereby thread-loops are passed through loops of needle-thread below the throat-plate and thread-loops are presented for passage of the needle-loops above the throat-plate.
5. In an overseaming sewing machine, the combination with the frame comprising a base-portion and an overhanging bracket-arm, a throat-plate upon said base-portion, a longitudinal crank-shaft mounted in bearings in said base-portion, a reciprocating needle-bar carrying an eye-pointed needle and mounted in bearings in said bracket-arm inclined in respect of said throat-plate and lying in a plane transversely of said shaft, needle-bar operating mechanism comprising a longitudinally extending actuating rock-lever movable upon a fulcrum intermediate its ends substantially perpendicular to the needle-path, a collar fixed to said needle-bar and provided with a thread-eye, a link connection intermediate said collar and the forwardly projecting arm of said rock-lever, a crank-rod with one end embracing the crank of said crank-shaft and the other end connected with a rearwardly extending arm of said rock-lever, a thread-guiding member fixed upon the bracket-arm and having a thread-eye adjacent said needle-bar, a thread-controlling member carried by and movable with said rock-lever and provided with a plurality of thread-eyes either of which is adapted to engage the needle-thread intermediate the thread-eyes of said collar and said fixed thread-guide, and over-

seaming looper-mechanism arranged beneath said throat-plate and comprising two independent thread-carriers movable in parallel planes perpendicular to said throat-plate and at an inclination to said needle-path, and means for actuating said loopers whereby thread-loops are passed through loops of needle-thread below the throat-plate and thread-loops are presented for 10 passage of the needle-loops above the throat-plate.

6. In an overseaming sewing machine, the combination with a frame comprising a base-portion and an overhanging bracket-arm 15 formed with upright columnar portion and lateral overhanging member of oblong cross-section twisted intermediate its ends and formed with adjacent transverse bearing bosses and carrying at the outer end a needle-bar guiding head comprising forwardly projecting lugs for the needle-bar and having an inclination similar to that of the adjacent portion of the arm, of a needle-bar journaled in the bearing lugs of said inclined head and 20 having an inclination similar to that of the latter, a rock-lever, a fulcrum for said rock-lever disposed perpendicular to said needle-bar and journaled in said bearing bosses, a link connection intermediate an arm of said 25 rock-lever and the needle-bar and disposed intermediate one of said bearing bosses and the bearing lugs for said needle-bar, overseaming looper mechanism mounted within said base-portion and comprising a plurality 30 of thread-carriers movable in planes substantially parallel with the columnar portion of the bracket-arm, and actuating mechanism for said thread-carriers whereby thread-loops are passed through loops of 35 needle-thread below the work and thread-loops are presented for passage of the needle-loops above the work in the production of an overseam.

7. In an overseaming sewing machine, the 40 combination with the throat-plate, a needle and means for reciprocating the same through said throat-plate, of a primary thread-carrying looper, a secondary thread-carrying looper having a lateral thread-engaging 45 shoulder, differentially acting thread-controlling devices each operating in conjunction with one of said loopers for controlling the thread of the other looper, and actuating 50 means for said loopers whereby the primary 55 looper carries loops of its thread through thread-loops presented by the needle and

the secondary looper passes loops of its thread through and deflects the primary looper loops and presents its own thread-loops for passage of thread-loops carried by 60 the needle.

8. In an overseaming sewing machine, the combination with the throat-plate, a needle and means for reciprocating the same through 65 said throat-plate, of a primary and a secondary thread-carrying looper, means for actuating said loopers to produce in conjunction with said needle an overseam, and thread-controlling devices having their operative 70 members each connected and movable with one of said loopers and adapted to engage the thread of the other looper for controlling the same in the production of stitches.

9. In an overseaming sewing machine, the combination with the throat-plate, a needle 75 and means for reciprocating the same through said throat-plate, of looper-carriers each mounted upon a fixed pivotal support, a primary looper fixed upon one of said looper-carriers and a secondary looper removably 80 mounted upon the other of said looper-carriers, a thread-controller having its operative member mounted upon the secondary looper-carrier for controlling the thread of the primary looper, and a thread-controller 85 having its operative member mounted upon the primary looper-carrier and adapted to control the thread of the secondary looper in the production of stitches.

10. In an overseaming sewing machine, 90 the combination with the throat-plate, a needle and means for reciprocating the same through said throat-plate, of looper mechanism coöperating with said needle in the production of overseam stitches, and comprising 95 a looper-carrier having a hub in the form of a sleeve, a shaft to which said sleeve is fitted, split bushings surrounding said shaft at opposite ends of said looper-carrier hub and adapted to bear upon the ends thereof, 100 fixed bearings surrounding said sleeves, and set-screws entering said bearings for engagement with the split bushings to clamp them upon said shaft and maintain them in position in said bearings.

In testimony whereof, I have signed my name to this specification, in the presence of two subscribing witnesses.

ALFRED GRIEB.
